UNITED STATES PATENT OFFICE

2,051,450

CIGARETTE CONTAINER

Hermon August Lubke, Clermont, Iowa

Application April 5, 1934, Serial No. 719,199

1 Claim. (Cl. 206—48)

My invention relates generally to cigarette containers, and particularly to a cigarette container forming a package of cigarettes including matches, and an important object of my invention is to provide a practical and convenient device of this character which is adequately efficient and inexpensive to warrant general use thereof.

It is also an important object of my invention to provide a container of the character described which is formed substantially of a single sheet of material and which may be made in different sizes for containing different numbers of cigarettes and matches.

Other objects and advantages of my invention will be apparent from a reading of the following description in connection with the drawing, wherein for purposes of illustration I have shown a preferred embodiment of my invention.

20 In the drawing:—

Figure 1 is a perspective view showing the cover flap closed.

Figure 2 is a transverse vertical sectional view taken through Figure 1 approximately on the line 2—2 but showing the cover flap open.

Figure 3 is a perspective view of the embodiment showing the cigarette holder removed.

Figure 4 is a section on line 4—4 of Figure 3.

Figure 5 is a plan view of the blank.

30 Figure 6 is a perspective view of the slide.

Figure 7 is a plan view of the blank from which the slide is formed.

Referring in detail to the drawing, the numeral 5 refers generally to the tube of the container in which the slide 6 is telescoped. The slide 6 is to contain the cigarettes 7 while the tube 5 contains both the slide and the matches 8.

The tube is formed from the blank shown in Figure 5 in a single piece comprising the body portion 9, the side portion 10, the back portion 11, the side portion 12 and the back flap 13. On the upper end of the main body portion is a flap or portion 14 and on the lower end of the main body portion 9 is the portion 15 which has a transverse row of holes 16 therein and the fold lines 21 and 22 arranged one on each side of said row and paralleling the same. The main part of the blank is folded on the lines 28 and 29, 30 and 31, and the flap 13 fastened in any suitable manner to a portion of the inner face of the back 11. The blank is slit on the upper portions of the fold lines 29 and 30 as shown at 29' and 30', the material between the slits forming an extension of the flap 14 and this extension is provided with a transverse row of

holes 17 and the pair of fold lines 24 and 25. Above the line 25 and below the line 24 are the match striking portions 18 and 19.

The extension of the flap 14 is first folded on the line 24 and then on the line 25 and inwardly of the box formed by the previous folding of the blank so that the row of holes 17 will be in the substantially horizontally arranged portion of the extension between the lines 24 and 25 as shown in Figures 1, 3, and 4, the flap 14 10 extending downwardly from the fold line 25 substantially vertical for the major portion of its length and parallel to a portion of the front 9, the parts 9 and 14 being connected together by a staple 27 or other fastening device. This 15 folding of the flap and the extension formed by a part of the front 9 places the horizontal portion carrying the holes 17 at a point spaced from the top of the box as shown.

The portion or flap 15 is folded upwardly into 20 the box and against the inner face of the front 9 and then folded on the line 21 and then on the line 22, so as to provide a horizontal portion between the fold lines 21 and 22 which carries the holes 16 as shown in Figure 4. The part 23 25 below the fold line 22 of the flap 15 extends downwardly a short distance in spaced relation to the main part of the flap 15 and then slopes downwardly into contact with said main part as shown in Figure 4. The flap 14 extends downwardly over the part 23 and its sloping portion and then continues downwardly into contacting relation with the lower portion of the part 15 as also shown in Figure 4. The lower ends of the front 9, the flap 15 and the 30 flap 14, are connected together by the staples 27. As will be seen from Figure 4, the folding of the flap 14 and its extension will place the striking surfaces 18 and 19 in parallel relation and immediately under the parts carrying the 35 holes 17.

The matches 8 pass downwardly through the holes 17 and 16 with their heads lowermost and said heads are located in the space formed by the portions 15 and 23.

Thus, by pulling upon the exposed end of the match its head will be drawn through a hole 16 and a hole 17 and as it passes between the striking surfaces 18 and 19 the head of the match will be ignited.

The slide herein generally designated by the numeral 6 comprises the rectangular main body portion 33 having on opposite sides flaps 34, 35 adapted to be bent on the lines 36, 37, respectively. On opposite ends of the body portion 55

33 are short flaps 38, 39 which form the top and bottom respectively of the slide. The flap 39 has a long extension 40 adapted to be positioned as shown in Figure 2 behind the match chamber; while the flap 38 has a shorter extension 41 which is adapted to assume the position shown in Figure 6 and in Figure 1 to hold the cigarettes in the container. The flap 38 and the extension 41 form the cover of the container which is displaceable in a conventional manner as shown in Figure 2 to expose the contents of the slide.

Although I have shown and described herein a preferred embodiment of my invention, it is to be definitely understood that I do not desire to limit the application of the invention thereto, and any change or changes may be made in material and structure and arrangement of parts, within the spirit of the invention and the scope of the subjoined claim.

What is claimed is:—

A container of the class described comprising a casing having its ends open and its front terminating an appreciable distance from one of said ends at the upper end of the front, a flap connected with the said upper end and extend-

ing inwardly a short distance and then downwardly in spaced relation to the inner face of the front, the inwardly extending portion having a longitudinally extending row of holes therein, a flap connected with the lower end of the front extending upwardly into contact with the inner face of the front and then bent at right angles and then downwardly a short distance at right angles to the inwardly extending portion and then sloping downwardly into contact with an intermediate portion of that part of the flap which contacts the front, the inwardly extending portion having a row of holes therein, and the space below the hole carrying portion receiving the heads of the matches, the stems of which pass through the two sets of holes, the first mentioned depending portion contacting the downwardly extending portion of the lower flap and extending to the bottom of the casing, and means for fastening the parts together, and striking surfaces on the adjacent faces of the first mentioned depending portion and the front immediately under the first mentioned hole carrying portion.
